UNITED STATES PATENT OFFICE.

RICHARD A. ROBERTSON, JR., OF PROVIDENCE, RHODE ISLAND.

PATTERN FOR PIPE-JOINTS.

SPECIFICATION forming part of Letters Patent No. 365,943, dated July 5, 1887.

Application filed October 16, 1886. Serial No. 216,407. (No model.)

To all whom it may concern:

Be it known that I, RICHARD A. ROBERTSON, Jr., of Providence, in the county of Providence and State of Rhode Island, have invented certain new and useful Improvements in the Manufacture of Pipe-Joints or "Special Castings;" and I do hereby declare that the following is a full, clear, and exact description of the invention, which will enable others skilled in the art to which it appertains to make and use the same, reference being had to the accompanying drawings, and to letters of reference marked thereon, which form a part of this specification.

15 My invention relates to the manufacture of metal joints, such as are used for connecting water-pipes, and which are known in the trade as "specials" or "special castings;" and my improvements consist in a multiform and interchangeable pattern for said castings having a central hollow sphere and a series of side patterns, the ends of which are adapted to be fitted at any place or places on the periphery of the sphere, all as more particularly herein-
20 after described and set forth.

25 Heretofore special castings have been made very long, in order to give room for the swing of the calker's hammer and to meet other conditions in their use. They have also been of great weight, on account of their length and the necessary thickness of flat or unstayed walls at the intersection of branches, particularly at the top and bottom of specials in which easy entrance-curves have been made.

35 For the manufacture of the ordinary forms of special castings a separate pattern and core-box is required for every form. The multiplicity of these forms is such as to cause a great expense in their manufacture and consequently render them costly to purchasers. For the same reason—multiplicity of patterns and core-boxes—it is not profitable and hardly possible to make the ordinary special castings of different thicknesses to suit the varying 40 thicknesses of ordinary pipes. The ordinary special castings have therefore always been suited to the heaviest grades of pipe, and they are consequently unnecessarily heavy and thick for all the medium and light weights. By far the 45 greater number of the pipes used are of these

latter grades, and the special castings are consequently in most cases wastefully heavy. By my invention all these objections and difficulties are overcome. By placing bells on any or all openings made in a hollow sphere a short 55 satisfactory casting is obtained free from the objections in use of short specials of the old form. When a hollow sphere (which is the strongest possible shape to resist bursting) is used for the body or largest part of my special, 60 it may be made comparatively thin, and on this account, as well as by the short length of the entire casting, produce a strong special with comparatively little metal. Further, by the methods of manufacture as hereinafter de- 65 scribed, I am able to produce special castings of varying weights to suit the varying weights of plain pipes with which the specials may be used, and so further produce a most economical casting with no waste metal.

70 By my invention I avoid the necessity for multiplicity of patterns and core-boxes, for with a pattern for one hollow sphere and a few separate and loose nozzles, bells, or spigots I can produce any conceivable variation 75 of angles, either vertical or horizontal, or any number or size of outlets, using the same hollow spherical pattern for the nucleus of each core-box, instead of having an entire and complete core-box for every pattern. There are 80 over six thousand of these combinations in ordinary demand, with no outlet larger than twenty-four inches diameter and suited for only one thickness of plain pipe. To produce all these castings would require more than 85 six thousand patterns, and, possibly, more than nine thousand core-boxes, each of which patterns or core-boxes would cost as much as the one sphere-pattern or each of the forty nozzle-patterns required by my invention to produce any or all of the above-mentioned six thousand castings and other desirable combinations, which it is not possible to produce otherwise. As a matter of economy in metal, however, I vary the sizes of my spheres to 90 suit the largest nozzle, bell, or spigot required, making the diameter of the sphere a little larger than that of the main pipe or largest "bell" which adjoins it. If but one sphere-pattern for all sizes of castings were used, those 95 100

with small outlets or nozzles would be unnecessarily large and heavy. For example, a sphere that would be the appropriate size for a twenty-four-inch nozzle would be all out of proportion in size and weight if it were used with a four-inch nozzle. By a still further slight increase in the number of sphere-patterns—that is, of different thicknesses—I am able to produce any multiple of the above-mentioned six thousand forms in varying weights or thicknesses.

In the accompanying drawings, Figures 1, 2, and 4 illustrate elevations of a few of the special castings made according to my invention. Fig. 3 illustrates a vertical section of Fig. 4. Figs. 5 and 6 illustrate in detail the pattern for making the form of casting as shown in Fig. 4, Fig. 6 being the nowel half of the pattern on the mold-board, with the nozzle-patterns closely abutted to the sphere-pattern in such a way as to produce a casting like Fig. 4.

Similar letters represent like parts in all the figures.

Referring to Figs. 5 and 6, A is the hollow spherical body or nucleus of the pattern, and $\alpha\alpha\alpha$ the patterns for making the bells, nozzles, or spigots. Any number of these loose pieces may be temporarily abutted to the surface of the sphere in any position on the mold-board, and the resulting casting may consequently be of any form as to size, nozzle, or feature.

The sphere-pattern A may have one or more holes from its periphery to its interior, through which may pass sand for the core rods or other supports for the core itself. The patterns being hollow and of the right shape for the casting, they form a core-box as well as a pattern, and are of course movable and can be placed in any combination. The patterns and core-boxes are one, and what serves for the pattern on the outside forms the core-box on the inside, and to make the core, sand and rods must be passed through holes in the pattern, the rods supporting the sand. These rods are used and support the core in the ordinary manner in the manufacture of the castings. The nozzle-patterns being hollowed out and touching the sphere only at their circumferences, the axial line of the outlet is always inevitably normal to the surface of the sphere. Each casting has an internal annular flange or lip, c , at the junction of the nozzles with the spherical body, against which the ends of the pipes, which are adapted to enter and be secured to said nozzles, may rest. The flanges c also prevent the ends of the pipes from entering into the spherical body of the casting and thus obstructing the interior of the same. By virtue of the enlargement of the casting at the intersection of the branches, or, in other words, by the greater sectional area of the sphere over that of the line-pipe, the velocity of flow of water or other material passing through it is greatly reduced, and the loss of head by im-

pact on the change of direction of flow correspondingly reduced.

By my invention many desirable and economical forms of special castings not obtainable in any other way can be made—for instance, a reducer and branch combination, as shown in Fig. 2, the sectional area of the main pipe B not being reduced before the branch C is taken off, as is the case in ordinary forms. 75

In the old form of casting the diameter of the line or supply pipe B is materially reduced before the outlet to the branch pipe C is reached. For instance, if the diameter of the supply pipe B is twelve inches, it will be reduced, say, 80 to ten inches before the branch C is reached, being gradually tapered from one end of the casting, with twelve inches diameter, to the other end of the casting, the diameter of which is about six inches. 85

Besides many other advantages which my special casting has over the forms now in use are the following: The specials are made by the least expenditure of metal, the form rendering them at the same time strong, compact, 90 and light. The hollow sphere, being in all parts in equilibrium under equal pressure in all directions, needs no staying or re-enforcement or additional metal to resist the strong pressure brought to bear on its interior surface. 95

A very important advantage of my new casting is that on account of its form such a small number of partial patterns are required, and the interchangeability of these to produce any conceivable form of special—virtually the production of any special without fixed patterns or core-boxes. By reason of the interchangeable parts of the pattern the power to produce similar shapes of varying thickness of body to suit 100 pipes of different weights with which specials 105 may be used is attained. By the placing of bells on all the openings, compactness, and the consequent avoidance of waste of the main pipe, is attained, for when a straight pipe is 110 necessarily cut to place the special in a particular location, when the old forms of special are used, the pipe cut off is either thrown away, or it is necessary to use an extra casting 115 in connection with it. By reason of the form 120 of the casting there is very little loss of head of the water or other material passing through it, which would take place if the casting were of the ordinary construction—that is, decreasing in diameter from its inlet to its branch outlet. 125

The method of making the casting is as follows: One half of the pattern is laid in the flask on the mold-board K, with its open part down, and the parts are placed as desired. Sand is then piled and rammed on top of the pattern 130 until it is level with the top of the nowel half of the flask. The whole—flask, board, and sand, with pattern—is then turned over and the board taken off, leaving the inside of the pattern exposed. Sand that had fallen inside of the pattern is cleaned out, and the balance of the pattern is then placed on the half of the

pattern in the sand. Sand is placed inside the pattern, and rods are passed through the same longitudinally. Sand is then rammed into the pattern through a hole in its top until 5 the inside of the pattern is filled, and this forms the core, which is supported by the rods above named. The top or cope half of the flask is then put on and filled and rammed with sand—that is, all around the outside of the upper 10 half of the pattern. The top or cope part of the flask is then lifted off and the top half of the pattern taken out, leaving the core exposed. The core is then lifted out and the lower half of the pattern taken out. Finally, 15 the core is laid back and rests on its bearings. The top half of the flask is then laid on and the metal poured in, which fills up the space which had been occupied by the pattern.

What I claim as new, and desire to secure 20 by Letters Patent, is—

1. A multiform and interchangeable pattern for pipe-joints or special castings, consisting of a central hollow sphere and a series of side patterns of different sizes, the ends of which are adapted to be fitted at any place or 25 places on the periphery of the sphere, all substantially as shown and described.

2. A multiform and interchangeable pattern for pipe-joints or special castings, consisting of a central hollow sphere of uniform 30 thickness throughout, and a series of side patterns of different sizes, the ends of which are adapted to be fitted at any place or places on the periphery of the sphere, all substantially as shown and described.
